US00D665363S

(12) **United States Design Patent**
Lin et al.

(10) **Patent No.:** US D665,363 S
(45) **Date of Patent:** ** Aug. 14, 2012

(54) **FAST TERMINAL BOX**

(75) Inventors: **Yueming Lin**, Ningbo (CN); **Lijun Duan**, Ningbo (CN); **Lizhi Chen**, Ningbo (CN)

(73) Assignee: **Renhe Photovoltaic Technology Co., Ltd.**, Ningbo, Zhejiang Province (CN)

(**) Term: **14 Years**

(21) Appl. No.: **29/387,802**

(22) Filed: **Mar. 18, 2011**

(51) **LOC (9) Cl. 13-03**

(52) **U.S. Cl. D13/156; D13/102**

(58) **Field of Classification Search D13/156, D13/102, 118, 133, 152, 155, 184, 199; 174/53, 174/54, 55, 58, 60, 66, 67; 361/641, 649, 361/679.01; 439/76.2, 207, 208, 374, 378, 439/380, 485, 486, 487**

(57) **CLAIM**

We claim the ornamental design for the fast terminal box, as shown and described.

DESCRIPTION

FIG. 1 is a front perspective view of the fast terminal box showing the design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.
